PHONOGRAPH

Erik Wennerbo, Motala, and Fritz August Svensson, Halmstad, Sweden, assignors to Industriaktiebolaget Luxor, Motala, Sweden, a Swedish joint-stock company

Application April 27, 1951, Serial No. 223,306

Claims priority, application Sweden May 8, 1950

3. Claims. (Cl. 274—9)

1

The present invention relates to phonographs of the type provided with means for changing the rotational speed of the record carrying member (turntable) between a higher value (78 R. P. M.) for the playing of the hitherto usual records and at least one lower value (33½ and 45 R. P. M.) for the playing of so-called long-playing records (LP records).

LP records require for their playing a needle or stylus whose shape is different from that of the hitherto usual stylus, and therefore it is necessary in phonographs for playing both kinds of records to use two different needles. The present invention provides for a simple and reliable means in such phonographs for automatically bringing the correct needle into working position when the rotational speed of the record carrying member is changed.

In the phonograph according to our invention a sleeve is rotatably mounted in the pick-up casing, a pin being yieldingly connected to said sleeve at its one end and carrying at its other end two phonograph needles projecting substantially radially therefrom and at an angle relatively to each other, of which needles one is a needle for playing standard records and the other is a needle for playing LP records, a mechanical connection permitting rotational movement of said needle-carrying pin being provided between the pin and the transducer unit of the pick-up for transmitting the needle vibrations to the latter unit, the speed changing means being connected to a movable member which is adapted to rotate the sleeve together with the pin and the phonograph needles upon actuation of said speed changing means so as automatically to move the correct phonograph needle into the working position.

For the explanation of the invention reference is had to the accompanying drawings which show a preferred embodiment of the invention.

In Fig. 1 of the drawings, 1 designates a pick-up casing. In the under side of this casing there is a rectangular recess 2 in the opposite end walls of which the two ends 3 and 4 of a sleeve 5 are rotatably mounted. The right hand end 4 of the sleeve engages a bore 9 in the casing 1 and contains a helical spring 7 and a ball 8 which is forced against the bottom of the bore 9 by said spring, and the left hand end 3 of the sleeve is inserted from below into a groove 10 formed in the casing 1 and is forced by the spring 7 axially against an abutment in said groove so that the sleeve 5 will be retained in the pick-up casing in the position shown. The sleeve 5 may readily be removed from the casing 1 by being displaced

2

to the right against the action of the spring 7 whereupon the left hand end 3 is moved out of the groove 10 and finally the right hand end 4 is pulled out of the bore 9.

5 Into the left hand end of the sleeve 5 a rubber stopper 11 is inserted. This stopper carries a pin 12 substantially coinciding with the axis of the sleeve 5 and carrying at its free end two radially extending needles 13 and 14, respectively, 10 which form right angles with each other.

The pin 12 engages a fork-shaped end of a second pin 15 which is connected to a transducer unit 16 for converting mechanical vibrations into electrical impulses and comprising a piezo-electrical crystal, for instance. The vibrations of the needle 13 (or 14) are thus transmitted to the transducer unit through the pins 12 and 15.

The middle portion 6 of the sleeve 5 is flattened and twisted a quarter of a revolution, as 20 shown. The twisted or helical portion 6 is adapted to cooperate with the fork-shaped end of an arm 17 which, in turn, is coupled to a control device for changing the rotational speed of the record carrying member and which is moved 25 longitudinally relatively to the sleeve 5 when the said control device is actuated, thereby rotating the sleeve 5 through a quarter of a revolution between its two end positions. If the needle 13 which is shown in the working position in the 30 drawing is a needle for playing standard records (recorded at a speed of 78 R. P. M.) and the needle 14 is one for playing LP records, changing the rotational speed from 78 R. P. M. to 33½ or 45 R. P. M. will cause the arm 17 to be moved 35 to the left whereby the sleeve 5 will be rotated anti-clockwise (as viewed from the left hand end 3 of the sleeve) and the needle 14 for LP records will be moved down into the working position.

Figure 2 shows the entire arm 17, one end of 40 which is fork-shaped for engaging the helical portion 6 whereas the other end of the arm forms a handle 18. The arm 17 has a cam surface 19 engaging a pin 20 which is carried by an arm 22 on the phonograph motor 21. The motor 21 has a 45 shaft 23 which in the position shown in the figure engages an intermediate wheel 24 which, in turn, engages an inner flange 26 on the turntable, said flange being concentric with the turntable shaft 27. The turntable has also an outer concentric flange 28. In the position of the various details 50 shown in the figure the motor shaft 23 rotates the intermediate wheel 24 which engages the flange 26 and rotates the turntable at a speed of 78 R. P. M. If the arm 17 is displaced upwards 55 in the direction of the arrow the pin 20 actuates

the cam surface 19 and moves the arm 22 and the motor 21 to the left so that the motor shaft 23 engages the outer flange 28 and thus rotates the turntable at a speed of 33½ R. P. M.

Modifications of the device as described above are conceivable within the scope of the appended claims.

What we claim is:

1. In a phonograph provided with means for changing the rotational speed of the record carrying member between a higher value for the playing of standard records and at least one lower value for the playing of LP records, a pick-up casing, a sleeve formed with helical guide means rotatably mounted therein, a pin yieldingly connected to said sleeve at its one end and carrying at its other end two phonograph needles projecting substantially radially therefrom and at an angle relatively to each other, one of said needles being a needle for playing standard records and the other being a needle for playing LP records, a transducer unit mounted in the pick-up casing, a mechanical connection permitting relative rotational movement provided between said needle-carrying pin and said transducer unit for transmitting the needle vibrations to the latter, a substantially linearly movable member connected to said speed changing means and adapted to cooperate with the helical guide means of the sleeve for automatically rotating said sleeve upon actuation of the speed changing means for moving the correct needle into the working position, the sleeve being rotatably mounted in the pick-up casing at its ends, an intermediate portion of the sleeve being flattened and twisted helically, and said helical portion being adapted to cooperate with the fork-shaped end of an arm which is connected to the speed changing means and is adapted to be moved thereby in the longitudinal direction of the sleeve upon actuation of said speed changing means for changing the rotational speed of the record carrying member.

2. In a phonograph provided with means for changing the rotational speed of the record carrying member between a higher value for the playing of standard records and at least one lower value for the playing of LP records, a tone arm, a transducer casing in said tone arm, said casing being kept against rotation around the length axis of the tone arm, a sleeve rotatably mounted in said casing, a pin yieldingly connected to said sleeve at its one end and carrying at its other end two phonograph needles projecting substantially radially therefrom and at an angle relatively to each other, of which needles one is a needle for playing standard records and the other is a needle for playing LP records, a transducer unit mount-

ed in the transducer casing, a coupling member secured to said transducer, a recess in the free end of said coupling member, an integral portion of said pin rotatably engaging said recess and 5 mechanical means connecting said sleeve with said speed changing means for automatically rotating said needle-carrying pin upon actuation of the speed changing means so as to move the correct needle into the working position.

3. In a phonograph provided with means for changing the rotational speed of the record carrying member between a higher value for the playing of standard records and at least one lower value for the playing of LP records, a tone 10 arm, a transducer casing in said tone arm, said casing being kept against rotation around the length axis of the tone arm, a sleeve rotatably mounted in said casing, said sleeve having an intermediate portion flattened and twisted helically, a pin yieldingly connected to said sleeve at its one end and carrying at its other end two phonograph needles projecting substantially radially therefrom and at an angle relatively to each other, of which needles one is a needle for playing standard records and the other is a needle for playing LP records, a transducer unit mounted in the transducer casing, a coupling member secured to said transducer, a recess in the free end of said coupling member, an integral portion of said 15 pin rotatably engaging said recess and mechanical means connecting said sleeve with said speed changing means, said means comprising a substantially linearly movable member having a fork-shaped end cooperating with said helical portion 20 of the sleeve and adapted to be moved in the longitudinal direction of the sleeve for automatically rotating said sleeve for bringing the correct needle into the working position upon actuation of said speed changing means for changing 25 the rotational speed of the record carrying member.
